STEEL MINE CAR

Filed Jan. 24, 1925

3 Sheets-Sheet 1

This technical drawing illustrates a complex mechanical assembly, possibly a reel or spool mechanism. The drawing is labeled 'FIG. 1' in the top left corner. The assembly features a rectangular frame with various internal components and a circular reel on the right side. Numerous parts are numbered, including:

- 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49.

The circular reel on the right is labeled with numbers 27, 28, 29, 30, 31, 32, 33, 34, 35, 36, 37, 38, 39, 40, 41, 42, 43, 44, 45, 46, 47, 48, 49. The drawing also includes several dashed lines representing hidden features or alternative states of the mechanism.

UNITED STATES PATENT OFFICE.

JAMES B. WOLF, OF GLEN RIDGE, NEW JERSEY, ASSIGNOR TO AMERICAN CAR AND FOUNDRY COMPANY, OF NEW YORK, N. Y., A CORPORATION OF NEW JERSEY.

STEEL MINE CAR.

Application filed January 24, 1925. Serial No. 4,515.

To all whom it may concern:

Be it known that I, JAMES B. WOLF, residing at Glen Ridge, Essex County, New Jersey, and being a citizen of the United States, have invented certain new and useful Improvements in a Steel Mine Car, of which the following is a full, clear, and exact description, such as will enable others skilled in the art to which it appertains to make and to use the same, reference being had to the accompanying drawings, which illustrate the preferred form of the invention; though it is to be understood that the invention is not limited to the exact details of construction shown and described, as it is obvious that various modifications thereof within the scope of the claims will occur to persons skilled in the art.

In said drawings:

Figure 1 is a view showing the improved mine car partially in side elevation and partially in longitudinal section;

Figure 2 is a view showing the mine car in top plan with one end portion shown in longitudinal section;

Figure 3 is a transverse sectional view taken along the line 3--3 of Figure 2; and

Figure 4 is a fragmentary view of the brake operating mechanism.

An object of this invention is to provide a mine car having an improved body construction which includes a bottom so constructed that brake operating means may be mounted in an improved manner and to permit the wheels being mounted upon axles positioned close to the bottom of the car and the wheels protected by hoods carried by the bottom of the car.

Another object of the invention is to so construct the bottom of this car that a longitudinally extending housing will be provided which is open at its lower side and will serve as a housing for the car couplers and also as a housing for a longitudinally extending shaft forming part of the brake operating mechanism.

Another object of the invention is to so construct this car body that the journal boxes of the wheel carrying axles may be mounted by means of pedestals extending up into the car and having the wheel protecting hoods connected with their upwardly protruding portions and further having their upwardly protruding portions secured to the side walls of the car.

Another object of the invention is to provide the car with an improved wall construction which will be very strong and at the same time of a simple construction.

This improved mine car is provided with a body portion having a bottom or flooring 1 formed of longitudinally extending floor boards, and side and end walls 2 and 3. These side walls are provided with upper and lower chords 4 and 5 which are formed of angle iron and are held in the proper spaced relation by posts 6 which are also formed of angle iron and serve not only as means for retaining the chords in the proper spaced relation but also serve as means for assisting in retaining the wall sheets 7 against the inner faces of the chords. These wall sheets 7 are formed of heavy sheet metal and from an inspection of Figures 1 and 2 it will be seen that the sheets are secured against the inner faces of the chords by rivets 8 and that similar rivets are also provided to secure the posts in place with the sheets 7 firmly held between the posts and the chords. The corner posts 9 in addition to retaining the chords 4 and 5 in proper spaced relation also serve as means for connecting the end walls with the side walls and as additional means for bracing the walls there have been provided bracing plates 10 which are secured upon the outwardly extending flanges of the upper chords 4 and to the outwardly extending flanges of the upper chords 11 of the end walls. It is not necessary to provide the end walls with lower chords as the sills 12 take the place of lower chords and the wall sheets and posts 13 of the end walls will be secured to the outer depending side flanges of the sills 12 by rivets or other suitable fasteners.

The flooring which is formed of longitudinally extending floor boards has its boards secured at their ends to the sills 12 by fasteners 14 and these boards are also secured by suitable fasteners to the upper flanges of the cross beams 15 and 16 which extend beneath the flooring and are secured to the lower chords of the side walls. Between the cross beams 15 and 16 the floor boards forming the side portions of the flooring have been removed so as to provide openings in the side portions of the car and intermediate the length thereof. It should further be noted that the flooring is pro-

vided with a longitudinally disposed open space intermediate its width and that a sheet metal housing 17 which is U-shaped in cross section is projected upwardly into the car 5 through this open space and is held in place by flanges 18 which engage the bottom of the flooring. These flanges are engaged by the cross beams 15—16 and by the sills 12 so that the housing will be very firmly held 10 in place. It should be also noted that there have been provided collars 19 which fit about the end portions of the housing within the car and are secured to the housing and to the end walls. This housing is 15 adapted to receive the draft means and also serves as a housing for a portion of the brake structure to be hereinafter described.

The draft means consists of the couplers 20 one of which will be provided at each end 20 of the car. Each of these couplers extends inwardly through an opening formed in the end wall and rests upon the sill 12. The inner end of the coupler rests upon a supporting plate 21 which extends transversely beneath the housing as shown in Figure 1 and a pin or bar 22 extends from the inner end of the coupler and through an abutment 23. A spring 24 is mounted upon this bar 22 between the abutment 23 and the inner end of the coupler so that the coupler will be yieldably held against inward sliding movement and a securing nut 25 is provided so that the bar 22 may be limited in its outward movement and the tension of 35 the spring 24 controlled by adjustment of this nut.

The axles 26 extend transversely beneath the car body and have their inner portions journaled in journal boxes 27 which are 40 mounted in pedestals 28 and engaged by the springs 29 which are positioned between the journal boxes and the upper end portions of the pedestals as shown in Figures 1 and 3. These pedestals are secured to the cross beams 15 and 16 by suitable fasteners 30 and have their upper end portions extending through the openings in the flooring of the car. Referring to Figure 3 it will be seen 45 that the pedestals are positioned in close contact with the wall sheets 7 of the side walls and that fastener bolts 31 are passed through the wall sheets and upwardly arched portions 5' of the lower chords 5 so that the pedestals will be firmly anchored 50 to these lower chords. This provides a very strong construction and at the same time permits the pedestals to be easily removed when necessary. The wheels 32 which are 55 carried by the axles 26 extend upwardly through the openings in the flooring and in order to protect these wheels and prevent material from passing through the openings there have been provided hoods 33 which 60 are secured to the inwardly extending side flanges 34 of the pedestals and to the floor 65

boards. From an inspection of Figures 2 and 3 it will be seen that the hoods have outstanding flanges 35 which are secured against the under face of the flooring by suitable fasteners and that when the pedestals and hoods are in place the openings formed in the flooring will be completely filled. Therefore the journal boxes, springs and wheels will be protected from damage as the material in the car cannot leak out 75 through these openings. This will also of course prevent loss of material placed in the car.

The brakes 36 are suspended from the cross beams 16 by hangers 37 so that they may have movement towards and away from the wheels and these brakes are connected with arms 38 which are carried by the pins 39 at the ends of the brake beam 40. This brake beam 40 extends transversely beneath the car and passes through straps 41 which serve to guide and limit vertical sliding movement of the brake beam. A link 42 is pivotally connected with the brake beam between the straps 41 and extends upwardly into the housing 17 with its upper end pivotally connected with the arm 43 extending transversely from the shaft 44. This shaft 44 extends longitudinally in the housing and is journaled in bearing brackets 45 secured to a side wall of the housing 17 and has its outer end portion extending through an opening formed in the end wall at one end of the car. This shaft 44 extends above the coupler as shown in Figure 1 and therefore it will not interfere with operation of the coupler. The extended outer end of this shaft is squared as shown at 46 in Figure 4 and carries an operating lever 47 which extends upwardly from the shaft and carries a tooth 48 for engagement with the rack 49. This rack extends transversely of the end wall and is secured with its major portion in spaced relation to the end wall. It will thus be seen that the lever may be swung to rotate the shaft and operate the brakes and that when moved to apply the brakes the lever may be securely held in a set position by engagement of the tooth 48 with the rack. Ordinarily this lever will be retained in the position shown in Figure 3 by the hook 49 carried by the short chain 50 and when in this position the brakes will be in an inoperative position.

What is claimed is:

1. In a car structure, a body having walls and a bottom, a housing extending longitudinally in the body and opening through the bottom of the body, brakes beneath the body, and brake operating means including a member extending longitudinally in the housing.
2. In a car structure, a body having walls and a bottom, a housing extending longitudinally in the body and opening through the bottom of the body, brakes beneath the body, and brake operating means including a member extending longitudinally in the housing.

- tudinally in the body and opening through the bottom of the body, brakes beneath the body, and break operating means including an actuating shaft disposed longitudinally in the housing.
3. In a car structure, a body having walls and a bottom, a housing extending longitudinally in the body and opening through the bottom of the body, brakes beneath the body, and brake operating means including a rotatably mounted actuating shaft extending longitudinally in the housing, and means for rotating said shaft for operation of the brakes.
- 15 4. In a car structure, a body having walls and a bottom, a housing extending longitudinally in the body and opening through the bottom of the body, brakes beneath the body, and brake operating means including a rotatably mounted actuating shaft extending longitudinally in the housing, and extending beyond one end of the body, means carried by the outer end portion of said shaft for rotating the shaft, and a rack carried by the car body for engagement by said lever.
- 20 5. In a car structure, a body having walls and a bottom, a housing extending longitudinally in the body and opening through the bottom of the body, brakes beneath the body, and brake operating means including a rotatably mounted actuating shaft extending longitudinally in the housing, a side arm extending from said shaft within the housing, a draw bar disposed transversely beneath the body, a link connecting said side arm with said draw bar for imparting movement to the draw bar when the shaft is rotated, links connecting the draw bar with said brakes for applying and releasing the brakes as the shaft is rotated, and means for rotating said shaft and retaining the shaft in a set position.
- 25 6. In a car structure, a body having walls and a bottom, a housing extending longitudinally in the body and opening through the bottom, draw bars mounted in the end portions of the housing and extending through the end walls of the body, brakes beneath the body, and brake operating means including a shaft extending longitudinally in the housing and through one end wall above one of said draw bars, and actuating means connected with the extended end of said shaft.
- 30 7. In a car structure, a body having walls and a bottom, axles extending transversely beneath the body, wheels upon said axles, the bottom of said body having openings and the wheels having their upper portions extending through the openings, pedestals secured to said bottom at the openings and extending above the bottom and disposed between the wheels and side walls of the body, wheel hoods secured to said pedestals and the bottom of said body and enclosing the projecting upper portions of said wheels, journal boxes for said axles, and springs between the journal boxes and upper portions of said pedestals.
- 35 8. In a car structure, a body having walls and a bottom, axles extending transversely beneath the body, wheels upon said axles, the bottom of said body having openings and the wheels having their upper portions extending through the openings, pedestals secured to said body and projecting upwardly through the openings between the wheels and side walls of the body, journal boxes for said axles carried by said pedestals, and hoods secured to said bottom and the inner side portions of said pedestals and enclosing the portions of the wheels extending above the bottom.
- 40 9. In a car structure, a body having walls and a bottom, the bottom having its side portions provided with openings adjacent the side walls of the body and in spaced relation to each other longitudinally of the body, axles extending transversely beneath said body and having their end portions below said openings, pedestals secured to said body beneath the bottom and extending upwardly through the openings, the projecting upper portions of the pedestals having inwardly extending side flanges, journal boxes for said axles carried by said pedestals for vertical sliding movement, springs between the journal boxes and upper portions of said pedestals, wheels upon said axles extending upwardly through the openings in said bottom, and hoods for the protruding upper portions of the wheels secured to the side flanges of the pedestals and to the bottom about the openings.
- 45 10. In a car structure, a body having a bottom and side and end walls, the side walls having upper and lower chords, posts connecting said chords, and side sheets; said bottom having openings adjacent the side walls and spaced longitudinally of the body, axles extending transversely beneath the body and having their end portions below the openings, pedestals secured to the body below the bottom and extending upwardly through the openings and secured to the lower chords, journal boxes for said axles carried by said pedestals, wheels upon the axles projecting upwardly through the openings, and hoods for the upper portions of the wheels secured to the pedestals and to the bottom about the openings.
- 50 11. In a car structure, a body having a bottom and side and end walls, said bottom having openings adjacent the side walls; the side walls comprising upper and lower chords, posts connecting said chords and side sheets secured to the chords and posts; the lower chords being formed of angle strips and being arched upwardly at the openings.
- 55 60 65 70 75 80 85 90 95 100 105 110 115 120 125 130

in the bottom, cross beams extending beneath the bottom at opposite sides of the openings, axles extending transversely beneath the body and having their end portions disposed below the openings, wheels upon said axles extending upwardly through the openings, pedestals secured to said cross beams and extending upwardly through the openings and secured to the arched portions of said

lower chords, journal boxes for said axles ¹⁰ carried by said pedestals, and hoods for the protruding upper portions of the wheels secured to the upper portions of the pedestals and to the bottom about the openings.

In witness whereof I have hereunto set ¹⁵ my hand.

JAMES B. WOLF.
